PORTABLE BUILDING

Clifford Roger Fleming-Williams, deceased, late of Hayes, Middlesex, England, by Kathrin Winifred Fleming-Williams, executrix, Cranford, England, assignor to Car Cruiser Caravans Limited, Hayes, Middlesex, England, a company of Great Britain

Application September 2, 1941, Serial No. 409,310
In Great Britain September 25, 1940

2 Claims. (Cl. 109—1)

This invention comprises improvements in or relating to portable buildings and has for its object to provide a simple form of such a building which is proof against bullets and bomb and shell splinters and is advantageously suitable for huts for military and like purposes.

According to this invention, a portable building is constructed with inner and outer walls spaced from each other and the space between these walls is charged with shingle or granite chips.

This building is suitably made in sections of box- or case-like nature filled with the shingle or granite chips and it is preferable for the sections to comprise both roof and wall parts so that the fitting together of the sections simultaneously produces wall and roof and a complete building is very quickly assembled.

Portable buildings of the above nature may obviously be of many and varied constructions and by way of example description will now be given of some advantageous practical constructions of sectional form which are illustrated in the accompanying drawings.

In these drawings—

Figure 1 is an elevation of a construction of building which is octagonal in plan.

Figure 2 is a section on the line II—II of Figure 1.

Figure 3 is a fragmental section of a window taken on the line III—III of Figure 1.

Figure 4 is a perspective view of a shutter for a window.

Figure 5 is an elevation of another construction of building which is of elongated form and of the nature, in appearance, of a marquee.

Figure 6 is a sectional plan of Figure 5.

Figure 7 is a sectional elevation of a cowl or ventilator for the buildings, and

Figure 8 is a section on the line VIII—VIII of Figure 7.

The construction illustrated by Figures 1 to 4 and which is of the nature of an octagonal hut, is composed mainly of eight sections of similar dimensions each embodying integral wall and roof parts 1 and 2 respectively. As will be seen from the figures the walls of the hut, composed of the parts 1, may slope inwardly from the bottom and the roof, embodying the parts 2 which may slope inwardly from the tops of the wall parts 1, may be of substantially pyramidal form so that both the wall and roof parts of the individual sections taper upwardly.

It may be mentioned at this point that similar sections can be used in the construction of the

ends of elongated forms of building such as shown in Figures 5 and 6 and described herein-after, and it will be useful to refer to the sectional plan view in Figure 6 in order the better to explain the construction of such sections. In Figure 6, the sections shown by A are similar to the sections of the building shown in Figures 1 to 4.

The said sections, as shown, are of box- or case-like construction and comprise inner and outer walls or skins, 3, 4, respectively, on a heavy wooden framework composed say of 6" x 2" section timbers 5, Figures 2 and 6, so that the walls or skins are spaced say 6" apart. The spacing may, of course, be varied up to 8" or more but it should preferably be not less than 6". At the side edges of the wall parts of the sections the timbers 5 are constructed and set so that these side edges are of bevelled nature and fit together on adjacent sections (see Figure 6). In addition to the frame timbers 5 at the several edges of the sections there may also be intermediate timbers for purposes of increased strength. Thus, for instance, there may be a central timber 6, Figure 6, extending upwardly in both the wall and roof parts 1, 2, respectively of the sections. In one or more sections, for instance as shown in the central section of Figure 1 or the central section at the left-hand end 20 of Figure 6, there may be a door or doors such as 7, in which case frame timbers 5 are extended about the door opening as indicated in Figure 6. The spaced walls or skins 3, 4 of the sections may be of one-piece form or sectional. They are shown built up on the timbers 5, 6 from boards which may be of tongue and groove type. As will be apparent, the side and central timbers of the roof parts of the hut sections extend upwardly at an angle in side view to those of the wall parts of the sections and continuous spaces 35 exist between the timbers from the top of the roof parts to the bottom of the wall parts. The roof parts may extend to a point or have a truncated upper end as shown. When the hut is erected, the spaces within the box- or case-like sections are filled with shingle or granite chips as indicated at 8, and to enable this material to be introduced removable panels 9, secured by plates 10 screwed to the frame timbers 5 or 5 and 6, are suitably provided at the upper and lower ends of the roof parts. If desired, the panels may be slidably or hingedly mounted with the upper panel suitably sliding or hinging downwardly and the lower one upwardly. It is 40 important that the hut sections should be trans-

portable for erection on a fresh site when desired and therefore one or more further removable panels 11, secured by plates 10 as before, is or are provided at the bottom of the wall part of the sections for allowing the sections to be emptied of their charge of shingle or granite chips. These panels 11 could, of course, be hingedly mounted and adapted say to hinge downwardly.

Openings such as 12 for ventilation or for windows 13, may be provided in the wall or roof parts of the sections and these preferably are made of inverted triangular shape so as to allow the shingle or granite chips to flow all round them when charging the sections and thus avoid the formation of empty pockets. As an example, and as shown in Figures 1 and 2, the hut may have such openings in alternate sections and if these sections have central timbers 6 as aforesaid, the latter in the wall parts 1, would suitably extend from the bottom timber 5 of the framework to the apex of timber frameworks, such as 130 in Figure 3, which frame the triangular openings. In any section having a door 7, the rectangular opening formed by the frame timbers 5 to accommodate the door, may be made large enough also to accommodate a liftable flap 14 which can be swung upwardly and then held open by a chain 15 anchored to the roof part of such section and engaged with a hook 16 on the flap. The door or doors and the flap or flaps may be mounted by hinges having removable pins 17 and the door or doors may have internal and external handles 18, and be secured by fastenings of any suitable or known form such as is shown at 19. The door or doors and the flap or flaps as shown are of box- or case-like nature similar to the hut sections and are also filled with shingle or granite chips. They may also have removable panels (not shown) on the inside for insertion and/or emptying of the shingle or granite chips as will be understood. At one edge of the door opening or openings the timber 5 and the corresponding timber of the door frame may be set at an incline in cross-section, as shown in Figure 6, so as conveniently to provide a stop to the door or doors on closure. The windows 13 are preferably of thick, bullet-proof glass, but if desired, shutters in the form of triangular wooden boxes 19, Figure 4, furnished with a handle 20, and charged with shingle or granite chips, may additionally be provided for fitting into the openings 12 on the inside of the hut for further protection. Or only a light wooden shutter need be used if only black-out purposes are to be served.

In assembling the sectional building or hut, the several sections, in empty condition, are fitted together to form the complete octagonal structure and are then suitably bolted or otherwise secured together through the side timbers 5, of the framework of both the roof and wall parts, for instance bolting may be done at the bottom of the wall parts 1 and at the top and bottom of the roof parts 2, as at 21 in Figure 2. As the sections are tapered and the side edges of the wall parts of the sections are bevelled, the sections fit together very closely and in effect each section forms a key to the next, the bolting imparting further strength. The appropriate panels referred to are then removed for the shingle or granite chips to be poured in and when the cavities of the sections are entirely filled they are replaced. The other panels allow of emptying when it is desired to move the structure. For

rendering the roof weather-tight it is suitable to provide a removable canvas or other waterproof cover 22 for the roof of the hut and this cover, which is shown broken away partly in

5 Figure 1, may also be extended wholly or partly down the walls of the hut. It suitably terminates a short distance below the eaves as shown and is secured there by rope 23 and hooks, spring-tensioned hooks, spring clips or similar devices as at 24.

When the roof parts of the hut sections have the upper end truncated as referred to a hole will appear at the apex of the roof of the erected hut and this may merely be covered by the waterproof cover 22 or, as shown in Figures 1 and 2, a board 25 may be fitted at the bottom of the hole and the latter then filled up with shingle or granite chippings as at 26 and the whole covered over and retained by the cover 22. The joints between the sections may be covered on the inside of the hut by wooden or other strips 27, as shown in Figure 2, to keep out the weather. A floor 28 may also be arranged in the hut as shown in Figure 2.

25 It will be understood that in accordance with the invention huts may be made of other shapes in plan than octagonal, for instance hexagonal or circular, by appropriate construction of the sections. Moreover and as shown by Figures 5

30 and 6, for example, the sectional construction enables buildings or huts of elongated form in plan to be provided by erecting certain of the sections at one place and others at another place, as at A, A, A, and A, A, A, in Figure 6, and joining the two sets by other sections, such as half-size sections B and sections C of non-tapering form, to provide sides for the elongated hut, these half-size and non-tapering sections each suitably

35 comprising wall and roof parts 1, 2 respectively like the tapering sections (except that the sections C would be constructed to meet at the ridge of the roof), and being charged with shingle or granite chips. Other parts in Figures 5 and 6

40 which are similar to parts shown in Figures 1 to 4, are numbered similarly to the latter parts, but it may be mentioned that Figures 5 and 6 illustrate two modifications which may usefully be adopted if desired. One of these modifications 45 is the employment of diamond-shaped ventilation openings or windows at 29 and the other relates to the use of ventilators or cowls at 30. Both modifications may be adopted in other constructions of hut herein referred to.

50 55 As will be realised, in regard to the first of the said modifications, the diamond shape of ventilation or window openings presents similar advantage to the inverted triangular form of Figures 1 and 2 as regards avoidance of empty pockets in the shingle or granite chip fillings of the sections.

55 In regard to the other modification, the ventilators or cowls at 30 may be of any suitable construction and, by way of example, reference 60 is directed to Figures 7 and 8 wherein a form is illustrated which comprises a base 31 adapted to fit in a hole of the roof, a duct part 32 uprising from an opening 33 in the base, and a hood part 34 fitted with a series of louvre-like strips 35 on 65 opposite sides thereof. The form of base 31 shown is intended for fitting the hole in the roof of a hut such as is shown in Figures 1 and 2 and it would be suitably modified if necessary in other cases as will be understood. Its ends appear cut 70 at an incline at 36 so that it wedges tightly in the

hole of the roof. The hood part 34 comprises strips 37 on the interior for resting it on the upper end of the duct part 32, and lever-headed screws 38 mounted in tapped holes in plates 39 on the ends of the hood part may be used for securing the latter when in position. Preferably, and as shown, the screws would also be used for securing the appropriately formed upper end of the cover 22 of the hut and for this purpose spring plates 40 on the hood part may be pressed by the screws against the upper end of the cover. If desired a wire mesh filter 41, may be fitted in the hood on the inside of the louvres as shown.

As will have been realised, the invention provides an advantageous construction of portable building or hut, the basic principle of which is the introduction of shingle or granite chips between inner and outer walls or skins and which can be introduced after the hut is erected for preference and when it is strengthened sufficiently to stand the heavy load. The shingle or granite chips render the walls proof against bullets and shrapnel and the structure is firm and solid, so that the building is very favourable for military and like purposes, particularly if a building is required to house wireless gear or other valuable or delicate apparatus. Moreover, the sections can be quickly filled and emptied without altering the structure of the sections and the cover 22 is easily removable so that erection and dismantling of the huts or buildings is readily effected. Where ventilation or window openings are provided they would preferably be arranged in the upper part of the walls or in the roof, as shown in the drawings for instance, to minimise danger from flying bullets or bomb or shell splinters.

It may be mentioned that apart from the protection offered against flying bullets, splinters and the like by the thickness of the layer of shingle or granite chips filled into the sections and the hardness and relatively high resistance of the shingle or granite chips to penetration, the shape of the shingle or granite chips, with either rounded or flat surfaces capable of exerting a deflecting effect on bullets and other missiles, affords further protection. It has been found that a six-inch layer of shingle will resist even armour-piercing bullets and in fact buildings in general in accordance with the invention can be made more bullet and shock proof than solid concrete buildings and yet are demountable practically without the use of tools. The great weight of the shingle or granite chips required to be car-

ried by the sections presents no undue disadvantage because the sections incline inwards and automatically lock themselves together like keystones or press one against another to take or balance the weight.

Finally, buildings of elongated form such as shown in Figures 5 and 6, may be made of greater length if desired by adding extra non-tapered sections, such as C, thereto.

10 5 What is claimed is:

1. A portable building comprising sections of box-like nature each embodying inner and outer walls of wood and a bordering wooden framework to which said wall parts are fixedly attached spaced from each other and providing a closed space within said framework and between said walls, a filling of loose stony material in said space of each of said sections, readily removable parts at upper and lower parts of each of said sections to facilitate filling and emptying respectively of said loose stony material into and from said space, said sections being of similar outline each comprising a unitary structure embodying side wall and roof parts of which the roof part tapers upwardly and is truncated at the top end so that a hole bounded by such end of the several sections is formed at the apex of the roof, and means for supporting a filling of loose stony material in said hole.
- 20 15 2. A portable building comprising sections of box-like nature each embodying inner and outer walls of wood and a bordering wooden framework to which said wall parts are fixedly attached spaced from each other and providing a closed space within said framework and between said walls, a filling of loose stony material in said space of each of said sections, and readily removable parts at upper and lower parts of each of said sections to facilitate filling and emptying respectively of said loose stony material into and from said space, said sections being of similar outline each comprising a unitary structure embodying side wall and roof parts of which the roof part tapers upwardly and is truncated at the top end so that a hole bounded by such end of the several sections is formed at the apex of the roof, and means for supporting a filling of loose stony material in said hole.
- 30 25 3. A portable building comprising sections of box-like nature each embodying inner and outer walls of wood and a bordering wooden framework to which said wall parts are fixedly attached spaced from each other and providing a closed space within said framework and between said walls, a filling of loose stony material in said space of each of said sections, and readily removable parts at upper and lower parts of each of said sections to facilitate filling and emptying respectively of said loose stony material into and from said space, said sections being of similar outline each comprising a unitary structure embodying side wall and roof parts of which the side wall part tapers upwardly and inclines inwardly of the building and the roof part tapers upwardly from the top of the wall part and also inclines inwardly of the building, whereby the several sections when assembled and filled by the loose stony material bear inwardly one towards 35 40 45 50 another on the opposite side of the building.

KATHRIN WINIFRED FLEMING-WILLIAMS,
Executrix of the Estate of Clifford Roger Fleming-Williams, Deceased.
